The ornamental design for a bottle wash feature, as shown and described.

DESCRIPTION

FIG. 1 is a perspective view of a bottle wash feature.

FIG. 2 is a side view of the bottle wash feature.

FIG. 3 is another side view of the bottle wash feature.

FIG. 4 is a front view of the bottle wash feature.

FIG. 5 is a rear view of the bottle wash feature.

FIG. 6 is a top view of the bottle wash feature; and,

FIG. 7 is a bottom view of the bottle wash feature.
In the drawings, dashed lines depict environmental structure
that forms no part of the claimed design.**1 Claim, 4 Drawing Sheets**|
